UNITED STATES PATENT OFFICE.

GEORGE OTIS DRAPER, OF HOPEDALE, MASSACHUSETTS, ASSIGNOR TO
SAWYER SPINDLE COMPANY, OF PORTLAND, MAINE.

BOBBIN-DRIVING MEANS FOR ROTATABLE SPINDLES.

SPECIFICATION forming part of Letters Patent No. 781,640, dated February 7, 1905.

Application filed December 8, 1904. Serial No. 235,919.

To all whom it may concern:

Be it known that I, GEORGE OTIS DRAPER, a citizen of the United States, and a resident of Hopedale, county of Worcester, State of Massachusetts, have invented an Improvement in 5 Bobbin-Driving Means for Rotatable Spindles, of which the following description, in connection with the accompanying drawings, is a specification, like characters on the drawings representing like parts.

In centrifugally-acting bobbin-driving means for rotatable spindles the bobbin is engaged and driven with the spindle by or through the medium of radially-movable and 15 loosely-connected clutch members rotatable with the spindle, the centrifugal force causing said members to firmly engage the chamber in the head of the bobbin. Such apparatus is very efficient and permits the easy removal of the bobbin or its application to the 20 spindle while the latter is running at speed, as the clutch members are readily pushed inward temporarily at such time; but owing to the character of the driving means the bobbin-head will sometimes move laterally under an 25 unbalanced load. This slight movement causes undesirable vibration and tends to affect undesirably the proper operation of the apparatus.

My present invention relates to the type of 30 spindle apparatus hereinbefore referred to; and it has for its object the production of novel means for overcoming the objection just noted, while at the same time providing a vertical support or rest for the bobbin when applied to the spindle.

In accordance with my invention the spindle is provided with a bobbin-rest having a flared or inclined surface so constructed and 35 arranged that it will be substantially tangential to the lower end of the bobbin, and while vertically supporting the same side movement or vibration of the head of the bobbin is prevented without any possibility of a tight fit 40 between the bobbin and the rest. Thus the bobbin may vary considerably in diameter, owing to changes in the humidity of the at-

mosphere, dampness of the yarn, or variations in temperature, without interfering with the proper operation of the apparatus.

50

The various novel features of my invention will be fully described in the subjoined specification and particularly pointed out in the following claims.

Figure 1 is a side elevation of a rotatable 55 spindle of the centrifugally-acting clutch type with one embodiment of my invention applied thereto; and Fig. 2 shows the bobbin-rest and lateral guard broken out and in section, the lower end or head of a bobbin being shown in 60 operative position on the spindle.

Inasmuch as the centrifugally-acting bobbin-clutch or driving means forms no part of my invention *per se*, such means may be of any well-known form, and herein I have illustrated the same as that shown and described in United States Patent No. 772,599, dated October 18, 1904.

The spindle A, whirl W, having an upturned sleeve w, by which it is rigidly secured to the 70 spindle, the centrifugally-acting clutch members 3, and the retaining-lips 7 thereon may be and are all substantially as in said patent and operate as therein set forth. In the present embodiment of my invention the head 75 w' of the sleeve w has an upturned cup-like portion 1 surrounding the lower ends of the clutching members, the inner face 2 of said portion 1 being made inversely frusto-conical—that is, it presents an annular upwardly 80 and outwardly flared surface concentric with the spindle, the angle of inclination being such that the face 2 will always be substantially tangential to the lower end b^x of the head b of the bobbin B, Fig. 2. From an inspection of Fig. 2 it will be seen that while the 85 bobbin is thus supported vertically by the inclined face 2 it is also restrained thereby from lateral movement or vibration. There can never be any tight or holding fit between the bobbin and the rest, owing to the angularity of the latter, the bobbin-rest having no function whatever in driving the bobbin with the spindle. Furthermore, the slight changes in

90

the size of the bobbin, due to shrinkage or swelling, have no effect on the efficacy of the bobbin-rest, for the bobbin will be supported thereon a little higher or a little lower, according to the increase or decrease in the bobbin diameter at its butt. As a matter of fact, while such change in diameter would interfere materially with the proper fit in a cup-driving device it actually makes but little

difference in the vertical height of the bobbin with my present invention. The bobbin will always bottom on the inclined face 2 and without possibility of wedging or binding, the centrifugally-acting clutching means effecting

the sole driving engagement with the bobbin within the chamber b' thereof, Fig. 2.

Having fully described my invention, what I claim as new, and desire to secure by Letters Patent, is—

1. The combination with a rotatable spindle provided with centrifugally-acting bobbin-clutching means to engage and drive the bobbin, of a bobbin-rest rigidly attached to the spindle and having an annular flaring face to engage the lower end of the bobbin substantially tangential thereto.

2. The combination with a rotatable spindle provided with centrifugally-acting bobbin-clutching means to engage and drive the bobbin, of the cup-like bobbin-rest attached to the spindle and surrounding the lower end of the clutching means, and having a flaring face to form an annular seat for and substan-

tially tangential to the lower end of the bobbin while preventing lateral movement thereof. 35

3. The combination with a rotatable spindle provided with centrifugally-acting bobbin-clutching means to internally engage the head of and drive the bobbin, of an attached bobbin-rest upwardly flared to contact externally 40 with the lower end of the bobbin and vertically support the same while preventing lateral vibration thereof.

4. The combination with a rotatable spindle provided with centrifugally-acting bobbin-45 clutching means to internally engage and drive the bobbin, a whirl, and a sleeve rigidly attaching it to the spindle, of an inverted frusto-conical bobbin-rest on the sleeve to loosely receive and vertically support and prevent lateral movement of the bobbin-head.

5. The combination with a rotatable spindle provided with centrifugally-acting bobbin-clutching means to engage and drive the bobbin, of a bobbin-rest attached to the spindle 55 and having a frusto-conical face to engage the lower end of the bobbin substantially tangential thereto.

In testimony whereof I have signed my name to this specification in the presence of two sub- 60 scribing witnesses.

GEORGE OTIS DRAPER.
